UNITED STATES PATENT OFFICE.

JOSEPH BUTCHER, OF BROOKLYN, NEW YORK

MOVING-PICTURE APPARATUS.

1,114,730.

Specification of Letters Patent.

Patented Oct. 27, 1914.

Application filed October 16, 1911. Serial No. 655,059.

To all whom it may concern:

Be it known that I, JOSEPH BUTCHER, a citizen of the United States, residing at Brooklyn, county of Kings, State of New York, have invented an Improvement in Moving-Picture Apparatus, of which the following description, in connection with the accompanying drawing, is a specification, like characters on the drawing representing like parts.

This invention relates to moving picture projection apparatus of that type adapted to use an opaque picture-carrying strip which has thereon a series of pictures to be projected on the screen and which is provided with means to project the images of said pictures. One of the advantages of this type of apparatus over that commonly used in which the pictures are on a transparent parent film, is that it eliminates the danger due to the use of a film made of a highly-combustible material, such as is commonly used in the production of the transparent films. An opaque picture-carrying strip can be made of substantially non-combustible material or at least of very slow-burning material, and the use of a strip of this type rather than one made of celluloid or other combustible material obviates almost entirely any fire danger. Moreover, where an opaque picture-carrying strip is used the pictures thereon can be readily colored, thus making it possible to throw colored moving pictures on the screen.

One of the objects of my invention is to provide a novel projection apparatus adapted to use an opaque picture-carrying strip in which the entire mechanism for feeding and supporting the picture-carrying strip is located at one side of the axis of the projecting lens, thus making it possible to produce a much more compact apparatus than where the picture-carrying strip is fed across or transversely of the axis of the projecting lens, as is usual in devices of this nature.

Other features of my invention will be more fully hereinafter described and then pointed out in the appended claims.

Referring now to the drawings wherein I have illustrated a selected embodiment of my invention, Figure 1 is a view showing a general arrangement of projecting apparatus and lamp; Fig. 2 is a side view of the projecting apparatus; Fig. 3 is a vertical section thereof on substantially the line $x-x$, Fig. 6; Fig. 4 is a fragmentary sec-

tional view of the strip-feeding mechanism on the line $e-e$, Fig. 6; Fig. 5 is a fragmentary end view of the light hood; Fig. 6 is an end view of the projecting apparatus with the light hood shown in section on the line $f-f$, Fig. 3; Fig. 7 is a detail view of the strip-feeding mechanism; Fig. 8 is a longitudinal sectional view on substantially the line $y-y$, Fig. 2; Fig. 9 is a section on the line $a-a$, Fig. 8; Figs. 10 and 11 are plan and side views of the escapement of the intermittent feed; Fig. 12 is a view of the picture-carrying strip; Fig. 13 is a side view of the projection apparatus showing the opposite side from that shown in Fig. 2; Fig. 14 is a view on substantially the line $b-b$, Fig. 6; Fig. 15 is a section on the line $c-c$, Fig. 16; Fig. 16 is a section through the line $d-d$, Fig. 6; Fig. 17 is an enlarged section on the line $e-e$, Fig. 3.

The picture-carrying strip is shown at 1 and it may be made of any suitable material on which pictures can be printed either by the photographic or any other process. Said strip, which is shown in detail somewhat in Fig. 12, will have a series of picture sections 2 on each of which is a picture, the various pictures going together to make up the continuous moving picture. These pictures which are printed on the strip might be printed directly from the film which is at present commonly used in moving-picture machines. This strip 1 is sustained by a strip-supporting and feeding mechanism which is herein shown as carried by a suitable stand or frame 3. While it would be within my invention to employ a strip-supporting and feeding mechanism of any suitable type adapted to properly support the strip and to feed it with an intermittent motion, yet the mechanism herein shown is what I regard as a practical one for this purpose.

As illustrated, the stand 3 is provided with two sides or cheek pieces 4 and 5 which sustain the strip guiding and feeding rolls. These rolls comprise a continuously-driven feeding roll 6, which is shown as having teeth or projections 7 thereon to engage the apertures 8 formed in the strip 1, a guiding roll 9 and an intermittently-acting feeding roll 10 which is also provided with teeth 11 to work in the apertures 8 of the strip. The continuously-rotating roll 6 may be driven by any suitable mechanism. As herein shown, the shaft of said roll has fast

thereon a gear wheel 12 situated outside of the cheek piece 4 and meshing with a pinion 13 on a driving shaft 14. This driving shaft, which is journaled partly in the cheek piece 4 and partly in a bearing or bracket 15, has fast thereon a pinion 16 meshing with and actuated by a driving gear 17 fast on a shaft 18 journaled in suitable brackets 19 carried by the frame 3 and provided with a handle 20 by which it may be turned. The shaft 14 is also preferably provided with a balance wheel 210 which operates to steady the action of the device. The guide roll 9 is also preferably positively driven, and for this purpose I employ a gear 21 which meshes with and is driven by the gear 12 and is fast on the shaft 22 of the roll 9.

The picture-carrying strip 1 is delivered to the feeding roll 6 through a guide 23, and said strip may be sustained on rolls 94 and 95 that are shown as secured to the underside of the table 96.

Situated between the guide roll 9 and the intermittently-acting feed roll 10 is a strip support 24 over which the strip passes and which supports the portion of the strip that is illuminated, as will be presently described. This strip support may be of any suitable or convenient construction and in the embodiment of the invention herein shown it is in the form of a plate extending between the cheek pieces 4 and 5 and supported thereby and preferably it is provided with the extension 25 which overlies the central portion of the feed roll 10 between the sets of teeth 11 thereon.

26 designates generally an objective or projecting lens for projecting the image on the screen. This lens can conveniently be carried by the frame 3, and in the present embodiment of the invention is situated above the strip-feeding and guiding mechanism so that all the operating mechanism is compactly situated below the projecting lens.

37 designates a source of illumination which may be an electric lamp or any other device. This is arranged to throw a beam of light upon the portion of the strip which is sustained by the strip support 24 thereby to illuminate such portion and means are employed to reflect an image of the illuminated portion of the strip into the projecting lens 26. Any suitable reflecting means may be employed, that shown being a mirror or reflector 27, and said reflector may be supported in proper position in any appropriate way. I prefer, however, the construction shown wherein it is secured in the upper side or roof 28 of a light hood 29 having two sides connected by a bottom 30, the latter being placed to overlie the portion of the picture-carrying strip sustained by the support 24 and having therein an opening 31 of a size to expose one of the picture

sections 2. The lamp 37 will preferably have suitable condensing lenses associated therewith which are arranged to collimate a beam of rays and direct said beam through the aperture 31 onto the exposed picture section 2. The light rays from this illuminated picture section 2 which strike the reflector 27 are reflected thereby into the projecting lens 26 so that an image of the picture is projected through said lens onto the screen.

The light hood 29 will preferably be movably mounted so that it can be thrown up out of the way and thus uncover the strip 1 thereby facilitating the feeding of the strip 80 into the machine. As herein shown this light hood is hinged to the lens casing, as shown at 32, and the sides thereof are extended downwardly, as at 33, to form a handle by which the hood may be swung up 85 out of the way about its pivot, as shown in dotted lines Fig. 13. These sides 29 are shown as situated between side plates 34 carried by the frame and I have shown said side pieces as provided with locking projections 35 adapted to enter recesses 36 formed in the side pieces 34 whereby the light hood will be locked in its operative position. By forcing the side extensions 33 together, however, as would be naturally 95 done in taking hold of them for lifting the light hood up, the lock can be released so as to permit said hood to be swung up out of the way.

As stated above the feed roll 10 is intermittently rotated as usual and necessary in the feed devices of moving-picture machines. It would be within my invention to employ any suitable mechanism for thus giving the feed roll its intermittent movement, but I 105 prefer to use the construction herein illustrated and which has been made the subject matter of another application filed by me October 16, 1911, Se. No. 655,060, and the construction of which will now be briefly 110 described.

The feed roll 10 is loosely mounted on a spring-actuated member 38 which in turn is loosely mounted upon a shaft 39 that is suitably journaled in the cheek pieces 4 and 5 and has a gear 40 thereon which meshes with and is driven by an idler 41 that in turn meshes with the pinion 13, as seen in Fig. 14. The shaft 39 is, therefore, continuously rotated. Situated within the member 120 38 is a spring 42, one end of which is fastened to the shaft 39, and the other end of which is secured to the member 38, thus establishing a spring or yielding connection between these parts. The member 38 has 125 fast therewith a wheel or flange 43 provided with a plurality of arms 44 and these arms coöperate with a let-off wheel 45 that is carried by a shaft 46 mounted in suitable bearings 47 carried by the cheek piece 4. 130

This shaft 46 is geared to the shaft 14 through the bevel gears 48 and thus has a continuous rotary motion. The let-off disk 45 is provided with an inclined slot 49 there-
 5 in which is brought into register with the path of movement of the pins 44 once during each revolution of the shaft 46. The continuous rotation of the shaft 39 tends to wind up the spring 42 and to maintain one
 10 of the arms 44 against the underside of the disk 49, as shown in Fig. 16. When during the rotation of the disk the slot 49 comes into line with the path of movement of the pins 44 the pin in engagement with the disk will
 15 pass into said slot and will move up through the slot as the disk rotates. Owing to the inclination of the slot, however, the pin 44 will not pass out from the slot 49 until the bottom end of the slot has been carried be-
 20 yond the path of movement of the pins so that when the pin is released from the slot and the spring 42 drives the member forward the next pin will strike the disk 45 and thus prevent further rotation of the
 25 member 38 until the let-off disk has made another complete turn. The feed roll 10 is clamped to the member 38 to rotate therewith, this being accomplished by providing
 30 said member 38 with a clamping flange 50 with which one end of the roll 10 engages and providing a clamping member 51 which is screw-threaded to the member 38 and is adapted to engage the other end of the roll 10. Under working conditions the roll 10
 35 is firmly clamped to the member 38 and will have the intermittent movement given to the said member by the escapement mechanism above described. The roll 10 may be unclamped from the member 38 and adjusted
 40 thereon as is necessary to adjust the strip so as to bring the picture sections thereon into proper alignment with the opening 31.

The escapement mechanism above described has the advantage that the intermittent movement thereof is exceedingly quick, so quick in fact that the time taken to move the strip forward is very small compared with the length of time which the strip is held stationary.

50 The use of shutters or other devices which are apt to cause a flicker in the projected image is not necessary with this apparatus.

From the above it will be seen that I have provided a novel moving-picture apparatus
 55 adapted to project images of pictures carried by an opaque picture-carrying strip and also that the entire mechanism for feeding and supporting the strip is very compact and is situated entirely below the projecting lens. The use of an opaque pic-
 60 ture-carrying strip enables me to use a strip which is formed of material which cannot be ignited merely by the heat of the lamp, and I can thus entirely obviate the danger of
 65 fire which is so inherent in the moving pic-

ture machines that employ the celluloid films. The arrangement of strip-feeding and supporting mechanism makes a very compact machine which can be inexpensively manufactured.

70 While I have illustrated one embodiment of my invention I do not wish to be limited to the precise details shown.

Having fully described my invention, what I claim as new and desire to secure by Letters Patent is:—

75 1. In a moving-picture projection apparatus, the combination with a projecting lens, of means to sustain a portion of an opaque picture-carrying strip below said lens and in a plane situated at an acute angle to the axis thereof, strip-feeding means, means to illumine said portion of the picture-carrying strip, and a reflector pivotally connected to the projecting lens and when in its operative position situated to reflect an image of the illumined portion of the strip into the projecting lens.

80 2. In a moving-picture projection apparatus, the combination with a projecting lens, of means to sustain a portion of an opaque picture-carrying strip in a plane situated out of line with the axis of said projecting lens and at an acute angle thereto, strip-feeding means, means to illumine said portion of the strip, and a reflector mounted on the projecting lens and situated to reflect an image of the illumined portion of the strip into said lens.

85 3. In a moving-picture projection apparatus, the combination with a projecting lens, of means to sustain a portion of an opaque picture-carrying strip in a plane situated out of line with the axis of said projecting lens, strip-feeding means, means to illumine said portion of the strip, and a reflector pivotally connected to the projecting lens and when in operative position situated to reflect an image of the illumined portion of the strip into the projecting lens.

90 4. In a moving-picture projection apparatus, the combination with a frame, of a projecting lens sustained thereby, a strip support sustained by the frame beneath the projecting lens and situated to maintain the portion of the picture-carrying strip supported thereby at an angle to but out of line with the axis of said projecting lens, strip-feeding means, means to illumine the portion of the strip sustained on said strip sup-
 95 port, and a reflector pivotally connected to the projecting lens and when in operative position situated to reflect an image of the illumined portion of the strip into said lens.

100 5. In a device of the class described, the combination with a stand, of a projecting lens carried thereby, a bracket secured to the stand beneath said lens, a strip support sus-
 105 tained by the bracket and situated at one side of and out of line with the axis of the

1
projecting lens, a picture-carrying strip sustained by said support, a hood having a bottom which overlies said support and is provided with an opening therein of a size to expose one section of said strip, means to illumine said exposed portion of the strip carried by the hand, and a reflector to reflect an image of the illumined portion of the strip into the projecting lens.

10 6. In a moving-picture projection apparatus, the combination with a projecting lens, of a strip support situated out of line with the axis of said lens and at one side thereof, means to feed a picture-carrying strip across said support, a hood pivotally connected to the projecting lens and formed

with a bottom which overlies the strip support and is provided with an opening therein of a size to expose one section of a picture-carrying strip, means to illumine the 20 section of said strip that is exposed through said opening, and a mirror sustained by said hood and situated to reflect an image of said illumined portion of said strip into the projecting lens.

25 In testimony whereof, I have signed my name to this specification, in the presence of two subscribing witnesses.

JOSEPH BUTCHER.
